UNITED STATES PATENT OFFICE.

CHARLES RAGNAR FREDSELL, OF NEWARK, NEW JERSEY.

LABEL-WIPING STATION.

Application filed April 5, 1924. Serial No. 704,432.

To all whom it may concern:

Be it known that I, CHARLES RAGNAR FREDSELL, a citizen of the United States, residing in the city of Newark, county of Essex, and State of New Jersey, have invented new and useful Improvements in Label-Wiping Stations, of which the following is a specification.

My invention relates to label wiping stations used with labeling machines, more particularly to the type of labeling machines in which the label applying means and the wiping means are accomplished with a step by step movement and with the articles in spaced relation, and has for its object to provide a mechanism that will wipe a label extending on three sides of an article to be labeled.

A further object is to provide a simple and compact wiping means that may be applied to double labelers and when combined with the mechanism embodied in an application for Letters Patent filed by me simultaneously with this case will furnish a mechanism for placing labels on all four sides of an article to be labeled.

The foregoing and other features of my invention will now be described in connection with the accompanying drawings forming part of this specification in which I have represented my mechanism in its preferred form, after which I shall point out more particularly in the claims those features which I believe to be new and of my own invention.

35 In the drawings:—

Figure 1 is an elevation of my wiping station.

Figure 2 is a plan view with the slide in position furthest away from the article to be labeled.

Figure 3 is a plan view with the slide in position after the label has been wiped and secured to the article to be labeled.

In the construction shown the entire wiping station is mounted on a slide 1 adapted to be reciprocated in a suitable stand 2 by any well known means attached to stud 3. The slide stand 2 is adapted to be secured to the table 4 of a labeling machine in proper relation with the delivery mechanism 5 carrying the articles to be labeled 6 in spaced relation. Inasmuch as the delivery mechanism is not a part of this invention it requires no further description here. It is sufficient to state that the articles to be labeled, having passed the label magazine at

which station a label is delivered and attached to the article to be labeled, it is brought up to the wiping station in a step by step motion. Synchronously with this movement the wiping station is reciprocated to and from the article to be labeled.

On the slide 1 I provide two similar rocker arms 10 each pivotally mounted at 11 and held in frictional contact with the slide by the spring 12 and friction plate 13. Mounted on the rocker arms 10 I provide arms 14 pivoted at 15 and held in contact with the arm 10 by the spring 16 providing a yielding connection with less tension than the spring 12 so that the arm 14 may outwardly yield without turning the arm 10 against the action of the spring 12 pressing the arm 10 against the friction plate 13.

The rocker arms 10 are each provided with an arm 30 which extends between two adjustable limit stops 31 and 32. These stops may be adjustable by any well known means as shown at 33. The object of these stops is to limit and control the motion of the wiping rolls.

The wiping rolls 40 are mounted in roll holders 41 which are provided with a pin 42 and slot 43 and are so arranged to readily engage a slot 52 and pin 53 of the roll arm 14 as will be readily understood by referring to Figure 1.

Mounted in suitable bearings 60 is a slideable grip pad rod 61 provided in its end nearest the path of the articles to be labeled with a grip pad 62 and held in its forward position by the spring 63. The object of this grip pad is to bring pressure contact between the label and the article to be labeled through a yielding contact during the advance of the wiping station and during the progress of the rolls to prevent the label from slipping out of its adjusted position.

The operation is as follows: The wiping slide is reciprocated to and from the article to be labeled. In Figure 2 the relative positions of the moving parts are shown. As the slide advances to a point where the grip pad 62 contacts with the label, the label is pressed against the article to be labeled and held in such position through a yielding pressure. The wiping rolls begin to follow the contour of the article to be labeled through the yielding pressure of springs 16 and continue over the label until the arm 30 contacts the limit stop 32 which rocks the arm 10 against the spring friction 12-13.

The slide is now ready for its return stroke and the working parts are held in that position until the arm contacts with the limit stop 31 which returns the rocker arms to 5 normal.

I wish it distinctly understood that my label wiping station described and illustrated is in the form in which I desire to construct it and that changes or variations may 10 be made as may be convenient or desirable without departing from the salient features of my invention and I therefore intend the following claims to cover such modifications as naturally fall within the lines of invention. 15

I claim:

1. In a labeling machine, wiper mechanism comprising a reciprocating slide, supports pivotally mounted thereon, roll retainers pivotally mounted on said supports, means for holding the roll retainers yieldably at one limit of its movement, means for controlling the pivoted movement of said support and means for limiting said movement. 20

2. In a labeling machine, wiper mechanism comprising a reciprocating slide, a support pivotally mounted thereon, a roll retainer pivotally mounted on said support, means for holding the roll retainer yieldably at one limit of its movement, and means for limiting the pivotal movement of said support. 30

3. In a labeling machine, wiper mechanism comprising a slide mounted for right line movement, supports pivotally mounted thereon, roll retainers pivotally mounted on each support, a spring for holding the roll retainers at one limit of its movement, an 40 arm extending from each support, and stops engaging said arms to control the pivotal movement of the support.

4. In a labeling machine, wiper mechanism comprising a slide mounted for right line movement, a support pivotally mounted thereon, means yieldably holding the support in any position to which it is moved, a roll retainer pivotally mounted on said support, means for holding the roll retainer 45 yieldably at one limit of its movement, and means for controlling the pivotal movement of the support. 50

5. In a labeling machine, wiper mechanism comprising a slide mounted for right line movement, a support pivotally mounted thereon, means yieldably holding the support in any position to which it is moved, a roll retainer pivotally mounted on said support, means for holding said retainer 55 at one limit of its movement, an arm extending from said support, and stops engaging said arm to limit the pivotal movement of the support. 60

6. In a labeling machine, wiper mechanism comprising a reciprocating slide, a

support pivotally mounted thereon, a roll retainer pivotally mounted on said support, means for holding the roll retainer yieldably at one limit of its movement, and means for limiting the pivotal movement of said support, and a grip pad mounted for sliding movement on said slide. 70

7. In a labeling machine, wiper mechanism comprising a slide mounted for right line movement, a support pivotally mounted thereon, a roll retainer pivotally mounted on said support, a spring for holding the roll retainer at one limit of its movement, an arm extending from said support, and stops engaging said arm to limit the pivotal movement of the support, and a grip pad mounted for sliding movement on said slide. 75

8. In a labeling machine, wiper mechanism comprising a slide mounted for right line movement, a support pivotally mounted thereon, means yieldably holding the support in any position to which it is moved, a roll retainer pivotally mounted on said support, means for holding the roll retainer yieldably at one limit of its movement, and means for limiting the pivotal movement of the support, and a grip pad mounted for 80 sliding movement on said slide. 85

9. In a labeling machine, wiper mechanism comprising a slide mounted for right line movement, a support pivotally mounted thereon, means yieldably holding the support in any position to which it is moved, a roll retainer pivotally mounted on said support, means for holding said retainer at one limit of its movement, an arm extending from said support, and stops engaging said arm to limit the pivotal movement of the support, and a grip pad mounted for sliding movement on said slide. 90

10. In a labeling machine, wiper mechanism comprising a reciprocating slide, a support pivotally mounted thereon, a roll retainer yieldably at one limit of its movement, and means for limiting the pivotal movement of said support, a grip pad slidably mounted on said slide and yieldable means for holding it at one of its movements. 110

11. In a labeling machine, wiper mechanism comprising a slide mounted for right line movement, a support pivotally mounted thereon, a roll retainer pivotally mounted on said support, a spring for holding the roll retainer at one limit of its movement, an arm extending from said support, and stops engaging said arm to limit the pivotal movement of the support, a grip pad slidably mounted on said slide and yieldable means for holding it at one limit of its movement. 120

12. In a labeling machine, wiper mechanism comprising a slide mounted for right line movement, a support pivotally mounted thereon, means yieldably holding the support in any position to which it is moved, 125

- a roll retainer pivotally mounted on said support, means for holding the roll retainer yieldably at one limit of its movement, and means for limiting the pivotal movement of the support, a grip pad slidably mounted on said slide and yieldable means for holding it at one limit of its movement.
13. In a labeling machine, wiper mechanism comprising a slide mounted for right line movement, a support pivotally mounted thereon, means yieldably holding the support in any position to which it is moved, a roll retainer pivotally mounted on said support, means for holding said retainer at one limit of its movement, an arm extending 15 from said support, and stops engaging said arm to limit the pivotal movement of the support, a grip pad slidably mounted on said slide and yieldable means for holding it at one of its movements.
- In testimony whereof I affix my signature in the presence of two witnesses.
